UNITED STATES PATENT OFFICE

129,603

DESIGN FOR A SINGLE STRIP HAMPER

William Fein, Jersey City, N. J.

Application July 9, 1941, Serial No. 101,994

Term of patent 3½ years

To all whom it may concern:

Be it known that I, William Fein, a citizen of the United States, residing at Jersey City, in the county of Hudson and State of New Jersey, have invented a new, original, and ornamental Design for a Single Strip Hamper, of which the following is a specification, reference being had to the accompanying drawing, forming a part thereof.

The drawing is a perspective view of a hamper showing my novel design; the back of the hamper being plain and the side not shown being identical with the one illustrated.

I claim:

The ornamental design for a single strip hamper, as shown and described.

WILLIAM FEIN.
